UNITED STATES PATENT OFFICE.

CHARLES E. HUXLEY, OF QUINCY, ILLINOIS.

PACKAGE RECEIVING AND DELIVERING DEVICE.

SPECIFICATION forming part of Letters Patent No. 655,901, dated August 14, 1900.

Application filed October 9, 1899. Serial No. 732,996. (No model.)

To all whom it may concern:

Be it known that I, CHARLES E. HUXLEY, of Quincy, in the county of Adams and State of Illinois, have invented certain new and useful Improvements in Package Receiving and Delivering Devices; and I do hereby declare that the following is a full, clear, and exact description thereof, reference being had to the accompanying drawings, and to the letters of reference marked thereon, which form a part of this specification.

This invention relates to improvements in apparatus for receiving mail-bags or other packages from railway-cars when in full speed and discharging same therefrom.

The invention consists in the matters hereinafter set forth, and more particularly pointed out in the appended claims.

In the drawings, Figure 1 is a plan of a mail-car, showing my improved receiving and discharging apparatus at the side thereof. Fig. 2 is a side elevation of the parts shown in Fig. 1 with the inclosure shown in section. Fig. 3 is a detail broken plan view of the receiving and discharging apparatus which is located at the side of the track. Fig. 4 is a detail section taken on line 4 4 of Fig. 3. Fig. 5 is a side elevation of the upper end of the receiving and discharging apparatus, showing a mail-bag in position thereon. Fig. 6 is a vertical section taken on line 6 6 of Fig. 4. Fig. 7 shows the receiving device which is located on the car. Fig. 8 is a sectional view taken on the line 8 8 of Fig. 7. Fig. 9 is a front view of the discharging device which is located on the car. Fig. 10 is a detail plan view with section taken on line 10 10 of Fig. 9.

As shown in the drawings, A indicates as a whole a mail-car, and at the side of the railway-track upon which said car travels at points thereon where mail is received and delivered are located a plurality of receiving and discharging devices, the construction being such that a mail-bag may be discharged therefrom and received upon the car and another mail-bag discharged from the car and received by said device.

It is one of the objects of this invention to provide in a single device which is located at the side of the railway-track mechanism which will both receive a mail-bag from a

passing car and deliver another bag to the said car, said mechanism being so constructed that the delivery of the mail-bag from the 55 car to the device will act to bring the mail-bag which is to be delivered to the car in position to be engaged by the usual or any preferred means for receiving mail-bags upon a 60 car.

As herein shown, such receiving and discharging device consists of an upright post B, having at its upper end a radial arm C, which is provided with means at its outer end for receiving a mail-bag from a passing 65 car, and having also arms D D', which when in position hold the mail-bag thereon radially from the post. Said arms D D' are provided with lugs d d' at their outer ends, which are engaged by the rings on the ends of the 70 mail-bag E in the usual manner, and said bags extend in the direction toward which the car is moving. Said arms D D' when in position to hold a mail-bag extend at right angles to the arm C, which carries the receiving mechanism and is so located that when a mail-bag has been delivered to the 75 said receiving mechanism on the arm C and said arm swung out of its operative position it will when it has moved through an arc of 80 ninety degrees carry the delivering-arms D D' into position to deliver the mail-bag to the receiving device on the car with said arms extending toward the car-track. The delivering-arms D D' are arranged to be thrown when 85 not in use outwardly in planes parallel with the post B, so as to be out of the way of passing trains. As herein shown, said arms are hinged at their inner ends to vertical plates or strips B² B³, which are connected with the 90 upper end of the post by means of laterally-directed parts b b', consisting, as herein shown, of right-angle bends which are connected side by side with said post. Pins d⁴ below the inner end of the upper arm afford a 95 shoulder to limit the downward movement of the arm. When the arms B² B³ are not engaged by a mail-bag, as shown in dotted lines in Fig. 5, the arm D' will by its own weight swing into a vertical depending position, 100 while the hinge which connects the arm D with the member B² is provided with a spring b², Fig. 3, which acts to normally hold said arm in its vertical position. The lugs d d'

are provided on their remote surface with 5 depressions for engagement with the rings of the mail-bag, and desirably springs d^2 d^3 will be provided, which overlie said depression and aid to hold said rings of the mail-bag in engagement with the lugs under usual conditions.

Next describing the receiving mechanism 10 which is attached to the arm C, these parts are made as follows: C' C² designate gripping-jaws mounted on the outer end of the arm C and in position when said arm C extends toward the track to receive the mail-bag from the delivering device on the passing car, the jaws for this purpose extending 15 in a direction generally perpendicular to the arm and opposite to the direction of movement of the car. Said jaws are each shown as made of the same shape and comprise curved central portions c c' and divergently-extending end portions c² c³, the parts between said curved and straight divergent portions being in contact with each other. The outer extremity of the divergent 20 end portions are located at a sufficient distance apart to receive a mail-bag and to provide for any lateral deviation of such bag from a true line due to the swinging of the car. The outer jaw C', as here shown, is attached rigidly to the arm, while the inner jaw C² is pivoted to the said arm by means 25 of a pivot-pin c⁴, so that the forward end thereof may be swung away from and toward said stationary arm C', and thereby permit said mail-bag to pass between said arms, where it will be held between the curved 30 portions c c' thereof. The rear ends of said jaws are shown as extending beyond the arm C, and a spring C³ is applied to said rear end 35 of the arms to normally hold the front ends thereof in contact with each other, said spring being attached to a screw C⁵ in the upper face of the arm C.

The arm C, which carries the receiving- 40 jaws, and the delivery-arms D D' are not attached directly to the post B, but are connected with a sleeve B⁴, which sleeve is rotatively mounted on the reduced upper end b³ of said post. Said arm C and the arms 45 D D' are connected rigidly to the said sleeve, so that the swinging arm C will act to give corresponding movement to the arms D D'. It is necessary, therefore, to lock but one of the arms, and in the present instance the 50 arm C is adapted to be locked rigidly to the post, and such locking means are constructed to be automatically released when a mail-bag is received from a passing car, so that the 55 discharging device may be moved into position to discharge another bag upon the car.

The locking means herein shown consists 60 of a disk E, which is connected rigidly with the upper end b³ of the post by means of a key e. Said disk is provided on its periphery with two notches E' E², which are separated a distance of ninety degrees of the circumferential disk, and with which notches a

dog C⁴, carried by the arm C, is adapted for alternate engagement to lock the arms in either of their two positions. As before stated, 70 said dog C⁴ is adapted to be released from the disk when the mail-bag is received by the jaws C' C², and the momentum of said bag is utilized to swing the receiving device out of its operative position and the delivering device into its operative position. This is accomplished in the present instance by the following mechanism: C⁵ designates a horizontal tripping-lever made of curved form and pivoted between its ends to a pin or bolt 80 c⁴. Said lever, as herein shown, is pivoted in a horizontal longitudinally-arranged slot in the outer end of the arm C. One end c⁶ of said lever extends laterally beyond the arm C, between the receiving-jaws C' C², 85 while the other end c⁷ is connected with the dog C⁴ by means of a link or connecting-rod C⁸. Said outer end c⁶ of the lever is provided with a curved plate c⁹, which is located below the gripping-jaws and extends at its 90 outer ends beyond the vertical planes of the inner margins of said jaws, so that when the jaws are opened to receive the mail-bag said bag will strike against said plate c⁹. When the mail-bag strikes against the divergent 95 ends c² c³ of said jaws, it will open said jaw C² by reason of the yielding of said jaw, and when it is entered between the curved portions of said jaws it will strike the plate c⁹, which will swing said lever C⁵ outwardly and 100 release said dog from the notch E', with which it will be engaged when in position to receive the mail-bag, and the force or momentum of the bag will swing the arm C around until arrested by engagement of the dog with the 105 notch E², as shown in Fig. 3. The same movement brings the delivery-arms into position for delivering another bag carried thereby to a receiving device on the car. After the bag has been delivered therefrom said arms will 110 assume vertical positions and be out of the way of passing cars.

A spring C⁷ is applied to the dog C⁴ to normally hold the same in engagement with either one of the notches E' E². As herein shown, 115 the arm C is provided with a longitudinal passage or opening, within which said spring C⁷ is located. Said dog C⁴ is attached to a rod C⁸, which has sliding engagement at its outer end with a nut C⁹, between which and 120 the dog the spring C⁷ is interposed. Said nut is made adjustable and has screw-threaded engagement with the interior of said longitudinal passage, so that the strength of said spring may be varied to hold the dog in engagement with the notches with greater or less pressure, as desired. The arm is provided on one side thereof with a slot c⁹, and said nut is provided in its periphery with spanner-holes, whereby they may be engaged 125 by a suitable instrument to adjust the same. The engagement of the dog with the periphery of the disk produces friction, which acts as a brake to retard the movement of said arm.

When the train is running at a high rate of speed, it will be desirable that the spring be placed under greater tension than when the train is running at a lower rate of speed, 5 so that the friction due to the pressure of the dog against the periphery of the disk will act to partially arrest the movement of the arm, and thereby decrease the force of the impact of the dog against the notch E². As a means 10 of enhancing such brake action as the arm C is approaching its final position I have herein shown the part e' of the periphery of the disk between the notches E' E² as made eccentric to the post R in a manner to increase 15 the tension of the spring as the dog approaches the notch E². This construction in connection with the adjustment of the spring enables me to adjust the device to correspond with the different rates of speed of trains 20 which may deliver mail to the said device.

I prefer to inclose said device to protect the same from the elements. Said inclosure is shown in Figs. 1 and 2 as consisting of side walls F, a rear wall F', a top wall F², and a 25 bottom wall F³, upon which the post is supported. As an additional means of breaking the momentum given the arm C when thrown in its inoperative position the rear wall of said inclosure may be provided with a spring- 30 buffer F⁴, as shown in Fig. 1, against which the rear ends of the receiving-jaws strike.

In Figs. 1, 2, and 3 the device is shown in the position in which it will be when the car is alongside of the same and has just received 35 a mail-bag from the car and the delivering device is in position for a mail-bag to be delivered therefrom to a receiving device on the car.

Referring now to the devices on the car for 40 delivering and receiving the mail, these parts are made as follows: The car herein shown is provided with two doors A A', one near the front and the other near the rear end of the car. At the front door of the car I provide 45 a delivering device consisting of arms G G', hinged to a strip G², which is attached to the door-jamb and in position to hold a mail-bag X, as shown in Fig. 9. The upper arm G is provided with a spring-hinge, so that it will 50 be swung upwardly out of the way when not in position to hold the mail-bag, while the lower arm swings downwardly in a vertical position by its own weight, as in a prior construction.

55 The receiving device on the car, which is designated as a whole by the letter H, is substantially like that employed on the local devices. Said device consists of a radial arm I, which is pivoted at its inner end to a post J, 60 which latter is connected with the rear door-jamb of the car, and receiving-jaws K K', which are made like the jaws C' C², before described. k designates the spring which holds 65 said jaws in their closed position, it being like the spring C³, before described. L designates a tripping-lever pivoted to the arm I, which is

connected, by means of a link M, with a dog N, which is adapted for engagement with notches o o' in a disk O, which is connected rigidly with the post J. Said lever L is provided at its outer end with a curved plate l, 70 which extends under the receiving-jaws K K'. The operation of this device is like that before described. The mail-bag when received between the jaws strikes the plate l and serves, through the lever L and the link M, to release the dog N from the notch o and swing the arm inwardly toward the car-door, where the mail-bag may be removed therefrom. In this instance the notch o', which is 75 engaged by the dog when the arm I is swung to its inoperative position, is located at a greater distance than ninety degrees from the notch o, so that when the lever is swung into position to engage the dog therewith said lever and receiving device will be located inside the car and easy of access to remove the mail-bag therefrom. The spring i may be made like the spring C⁷, before described, 80 whereby the tension of the spring may be adjusted to correspond with the speed of the train. The notches o o' may be located at such distances apart as may be desired in order to arrest the arm at a point most convenient in each particular instance. 85

In case the arm is swung completely into the car, as indicated by the construction shown in Fig. 7, the door may be left open to permit such movement. It may be desirable, however, in inclement weather to keep the 90 door closed, and I have shown one construction for permitting the arm to be swung inwardly into the car notwithstanding the main door is closed. Said means consist of auxiliary leaves or doors P P, which are connected 95 at their upper and lower edges to the upper and lower edges of an opening in the main door A' by means of spring-hinges p and open inwardly away from each other. With this construction when the arm is swung inwardly 100 by reason of engagement of the receiving-jaws with the stationary mail-bag the rear ends of said jaws will strike said doors and force the same open to permit the receiving device and the mail-bag to pass therethrough 105 and into the car, after which said spring-hinges will close the doors, as shown in Fig. 2. The position of said car receiving device when located inside of the car is shown in dotted lines in Fig. 7. 115

Should it ever become desirable or necessary to receive mail from and deliver it to two or more cars in the same train, this may be accomplished by providing as many receiving and delivering devices as there are cars 120 in the train to and from which mail is to be delivered and received. With this arrangement the first car on the train from which mail is to be delivered and received will deliver the mail to the first device and receive 125 it therefrom, the second car receiving its mail from the second device and delivering it there- 130

to, &c., it being understood that as each device is brought into operation and mail delivered to and received therefrom it will be moved entirely out of the way of the next car, 5 so that the receiving and delivering devices on the car and at the station may be exactly the same in construction and relative positions.

My invention has herein been shown and 10 described as adapted for receiving mail-bags from and delivering the same to mail-cars; but I do not wish to be restricted to such uses. It will be evident that only slight modifications of the receiving-jaws are necessary in 15 order to adapt the device for receiving and delivering other packages—as, for instance, newspaper-packages or express-packages—from moving trains. The principle of operation will be the same, and the device may be 20 used with equal advantage for mail-packages or express-packages as for mail-bags.

The device herein set forth, embracing the receiving and discharging mechanism for packages or mail-bags organized in one construction, whereby the operation of one is affected by the operation of the other, is of 25 great importance, for the reason that it greatly simplifies the receiving and discharging device. Moreover, the receiving and discharging 30 device being organized in one construction is more convenient in use than where two different and independently-acting devices are employed.

A further and important advantage arising 35 from the use of the construction described is that it is contained within a small compass and may be readily inclosed, as illustrated in the drawings. The packages discharged from said device and received thereby may therefore be protected from the elements and do not require such close attention by the agent having charge of the same as where the receipt and delivery of such packages are exposed to the inclemencies of the weather. 40 With the use of said device, therefore, the agent is not required to so closely watch the arrival of trains from which packages are to be received or to which they are to be delivered, but may place the package to be delivered 45 to the train on the device at his leisure and remove the package received by said device from the train at a time most convenient.

The construction and arrangement of the receiving device on the car herein shown and 50 described are of considerable importance, as the receipt of the package upon the train is entirely automatic and does not require the attention of the person having the same in charge. Moreover, said construction and arrangement permit the receipt of packages to 55 the car without the necessity of having the main door open.

While I have herein shown what I consider 60 to be a practical and in some respects a desirable embodiment of my invention, I do not 65 wish to be restricted to such construction, ex-

cept as hereinafter made the subject of specific claims.

I claim as my invention—

1. The combination with a receiving device 70 adapted to receive a package from a passing car, and a discharging device, of connections between said devices whereby, when a package is received by the receiving device from a passing car, the discharging device is 75 brought into position to deliver a package to said car, and a brake mechanism applied to said device to retard the movement thereof.

2. A package receiving and discharging device comprising an upright post, and receiving 80 and discharging arms pivoted to the upper end thereof at right angles to each other and rigidly connected together.

3. A package receiving and discharging device comprising an upright post, receiving 85 and discharging arms pivoted to the upper end thereof at right angles to each other, and means for locking said arms to the posts.

4. A package receiving and discharging device comprising an upright post, receiving 90 and discharging arms pivoted to the upper end thereof and adapted to be brought alternately into operative position, a notched disk rigid with the upper end of said post and a dog connected with said arms and adapted 95 for engagement with the notches of said disk.

5. A package receiving and discharging device comprising an upright post, receiving 100 and discharging arms pivoted to the upper end thereof and adapted to be brought alternately into operative position, a notched disk rigid with the upper end of the post, a dog on the receiving-arm adapted for engagement with the notches of said disk, and means for actuating said dog which are operated when 105 a package is received by the receiving-arm from a passing car.

6. A package receiving and discharging device comprising an upright post, receiving 110 and discharging arms pivoted to the upper end thereof and connected together, receiving-jaws on the outer end of said receiving-arm, and means operated when a package is received between the jaws from a passing car 115 to swing the receiving-arm out of its operative position and the discharging-arm into its operative position.

7. A package receiving and discharging device comprising an upright post, receiving 120 and discharging arms pivoted to the upper end thereof and connected together, a notched disk rigid with the post, a dog on the receiving-arm adapted for engagement with the notches of the disk, receiving-jaws connected with the outer end of the receiving-arm, and means operated when a package is received 125 by said jaws to release said dog from engagement with the disk and swing the parts out of and into their operative positions respectively.

8. A package receiving and discharging device, comprising an upright post, receiving 130

- and discharging arms pivoted to the upper end thereof and adapted to be brought alternately into operative position, a disk rigid with the upper end of the post, and a spring-pressed dog on the receiving-arm adapted to engage the notches of the disk and a lever connected with the dog and adapted to be oscillated when a package is received from a passing car.
10. A package receiving and discharging device, comprising an upright post, receiving and discharging arms pivoted to the upper end thereof and adapted to be brought alternately into operative position, a notched disk rigid with the upper end of the post, a spring-pressed dog on the receiving-arm adapted for engagement with the notches of said disk, receiving-jaws on the outer end of said receiving-arm and a lever located between said receiving-jaws and connected with said dog.
10. A package receiving and discharging device comprising an upright post, receiving and discharging arms pivoted to the upper end thereof, and connections between said arms which operate when one of the arms is swung out of its operative position to swing the other arm into its operative position.
11. A package receiving and discharging device comprising an upright post, receiving and discharging arms pivoted to the post adapted to be brought alternately into operative position, receiving-jaws on the outer end of said receiving-arm, one of which is pivoted to the arm and the other of which is rigid therewith, a notched disk rigid with the upper end of the post, a dog on the receiving-arm adapted for engagement with the notches of the disk and a tripping-lever between said jaws which is connected with the dog.
12. A package receiving and discharging device comprising an upright post, receiving and discharging arms connected with each other and pivoted to the post, receiving-jaws on the outer end of said receiving-arm, one of which is stationary with the arm and the other of which is pivoted thereto to move toward and away from the stationary arm, a spring applied to hold said pivoted jaw in engagement with the stationary jaw, a notched disk rigid with the upper end of the post, a dog on the receiving arm adapted for engagement with the notches of the disk, and a tripping-lever between said jaws which is connected with the dog.
13. A package receiving and discharging device comprising an upright post, receiving and discharging arms pivoted to the post adapted to be brought alternately into operative position, receiving-jaws on the outer end of said receiving-arm, one of which is rigid with the arm and the other of which is pivoted thereto, a notched disk rigid with the upper end of the post, a dog on the receiving-arm adapted for engagement with the notches of the disk, and a tripping-lever between said jaws and connected with the dog, said lever being provided on its forward end with a contact-plate against which the package strikes when received from the passing car.
14. A package receiving and discharging device comprising an upright post, receiving and discharging arms pivoted thereto and connected together, a notched disk rigid with the upper end of the post, a dog on the receiving-arm and adapted for engagement with the notches of said disk, means operated when a package is received from a passing car to release said dog from one of the notches and to swing the receiving-arm out of its operative position and the discharging-arm into its operative position, a spring applied to said dog to hold it in engagement with the notches and means for adjusting the tension of said spring.
15. A package receiving and discharging device comprising an upright post, receiving and discharging arms pivoted thereto and connected together, a notched disk rigid with the upper end of the post, a dog on the receiving-arm adapted for engagement with the notches on the disk, means operated when a package is received from a passing car to release said dog from one of the notches and swing the receiving-arm out of its operative position and the discharging-arm into its operative position, the periphery of said disk between said notches being made eccentric to the post.
16. A package-receiving device comprising a pivoted arm, a disk rigid with the pivot provided with two circumferentially-separated notches, a dog connected with the arm adapted for engagement with one of said notches when the arm is in operative position, and means for releasing said dog from said notch whereby the arm may be swung out of its operative position when a mail-bag is received thereby and bring the dog in engagement with the other notch.
17. A package-receiving device comprising a pivoted arm, a disk rigid with the pivot of the arm, a dog connected with the arm adapted for engagement with the notches of the disk, and means for releasing said dog from the disk whereby the arm may be swung out of its operative position when a package is received by said arm, said disk being constructed to constitute, in connection with said dog, a brake to retard the movement of the arm.
18. A package-receiving device comprising a pivoted arm, a notched disk rigid with the pivot of the arm, a dog connected with the arm adapted for engagement with the notches of the disk, means for releasing said dog from the disk whereby the arm may be swung out of its operative position when a mail-bag is received by said arm, a spring applied to the dog to hold it in engagement with the said notches, and means for adjusting the tension of said spring, said disk being constructed to afford a brake to retard the movement of the arm.
19. A package-receiving device comprising a pivoted arm, a disk rigid with the pivot of the arm and provided in its circumference with two notches, a dog on the arm adapted

for engagement with either of said notches, and means operated when a package is received by said device to release the dog from the notch engaged thereby and to swing 5 the arm out of its operative position, the periphery of said disk between said notches being made eccentric to the pivot of the arm.

20. A package-receiving device comprising a pivoted arm provided on its outer end with 10 a pivoted jaw and a stationary jaw, between which the package is received, and means for holding the pivoted jaw yieldingly in contact with the stationary jaw, said jaws diverging from each other both inwardly and 15 outwardly from their point of contact.

21. The combination with a receiving device comprising a pivoted arm, means for locking the said arm in its operative position and means for releasing it from its operative position 20 and swinging it in its inoperative position when a mail-bag is received thereby, of a discharging device comprising two vertically-swinging arms connected with the receiving device in a manner to be brought into 25 its operative position when the receiving device is moved out of its operative position, said arms being adapted to be swung into horizontal positions for engagement with the opposite ends of packages to be delivered to 30 the passing car and away from each other in vertical positions when not in use.

22. The combination with a car, provided with a sliding door which is provided with an opening which is closed by a swinging door 35 or leaf, of a package-receiving device which is adapted to receive packages from a stationary discharging device and to deliver the same to the interior of the car through said swinging door or leaf.

23. The combination with a car, of a receiving device comprising an arm which is pivoted to the door-jamb of the car and provided on its outer end with receiving-jaws adapted to engage the package, means for locking the arm in its operative position, means operated by engagement of the package with the receiving mechanism for releasing the locking mechanism and swinging the end of the arm and the package carried thereby into the interior of the car, and a brake mechanism for said arm embracing an eccentric part between the arm and its pivot.

24. The combination with a car, provided with a sliding door and provided with an opening which is closed by a swinging door or leaf, of a package-receiving device comprising an arm pivoted to the door-jamb and having on its free end receiving-jaws, means for locking said arm in its operative position 55 and means operated by the engagement of the package with the receiving mechanism to release the locking mechanism and to swing the outer end of the arm and the package

carried thereby into the interior of the car through said swinging door.

25. The combination with the receiving and discharging arms of a receiving and discharging device, and a common pivot for the arms, of connections between said arms which are operated when a package is received from a 70 passing car by the receiving-arm to bring the discharging-arm into its operative position, and an inclosure for said device which incloses the discharging-arm when the receiving-arm is in its operative position and into 75 which the receiving-arm, and the package carried thereby, is automatically moved when the package is delivered from the passing car to the receiving-arm.

26. The combination with a receiving device and discharging device comprising an upright post, and receiving and discharging arms pivoted to said post and which receiving and discharging arms are arranged at right angles to each other, of an inclosure for 85 such device within which the receiving and discharging arms are adapted to be alternately moved.

27. The combination with a receiving and discharging device, comprising an upright 90 post and receiving and discharging arms pivoted to the upper end of the post, which receiving and discharging arms are located at right angles to each other, of an inclosure for said device, which incloses the discharging-arm and the package carried thereby when the receiving-arm is in position to receive a package from a passing car, and means for automatically swinging the receiving-arm and the package received thereby 95 into the inclosure and the discharging-arm into its operative position which is operated by the delivery of the package from the car to the receiving-arm.

28. The combination with receiving and discharging arms which are adapted to be brought alternately into operative position, and which are pivoted to a common pivot, of a brake mechanism embracing an eccentric part between said arms and pivot.

29. The combination with receiving and discharging arms which are adapted to be brought alternately into operative position, of a spring-pressed dog for holding said arms in their operative position, and a brake for 115 retarding the movement of said arms embracing an eccentric part in engagement with said dog.

In testimony that I claim the foregoing as my invention I affix my signature, in presence 120 of two witnesses, this 30th day of September, A. D. 1899.

CHARLES E. HUXLEY.
